INKING ROLLER REMOVAL TRUCK FOR
NEWSPAPER PRINTING PRESSES

Arnold L. Imshaug, West Springfield, Mass., assignor to Alico, Inc., West Springfield, Mass., a corporation of Massachusetts

Application December 21, 1948, Serial No. 66,458

4 Claims. (Cl. 214--1)

1

This invention relates to equipment for handling inking rollers on an arch or unit type of newspaper printing press in the removal and installation of rollers on the press.

Inking rollers on this type of machine are heavy rubber covered cylinders weighing approximately 150 pounds. Their surfaces must be true and smooth and full efficiency requires removal for grinding or replacement at frequent intervals, whenever the surface is damaged or untrue. So far as I am aware devices and equipment now designed to handle such rollers require more or less heavy manual labor by pressmen in lifting the same in and out of the assembly.

It is an object of this invention to eliminate heavy and dangerous lifting and to provide a specialized truck unit to assist in the quick and efficient transfer of rollers to and from the printing press assembly.

These and other advantages will become apparent from the following disclosure taken in connection with the description of an embodiment of the invention as shown in its preferred form by the accompanying drawings, in which:

Fig. 1 is a diagrammatic end view of an arch type printing press showing various roller positions with the new truck shown partly in section and wheeled into position for removal of one of the rollers;

Fig. 2 is a similar view with the roller transferred from the press onto the truck;

Fig. 3 is a similar view showing the truck equipped to remove another roller from a higher position in the press;

Fig. 4 is a top plan of the truck with a roller supported thereon;

Fig. 5 is a side elevation of the truck shown in Fig. 4;

Figs. 6 and 7 are fragmentary views showing details of truck construction; and

Fig. 8 is a fragmentary view showing the mounting of a roller shaft in the press unit.

In Fig. 1 an arch or unit type newspaper printing press is shown in outline with spaced roller sets 1 and 2 mounted at each side thereof. In each set is shown a lower ink drum 3, two transfer inking rollers 4 located between drum 3 and an upper ink drum 5, an intermediate distributor inking roller 6 associated with drum 5, two upper transfer inking rollers 7, and in contact with inking rollers 7 a plate cylinder 8 which in turn is in contact with impression cylinder 9. As will be understood by those skilled in the art, the distributor roller 6 serves to spread and distribute ink evenly on the surface of drum 5. Trans-

2

fer rollers 4 and 7 between drums 3 and 5 and between drum 5 and plate cylinder 8 also serve to spread the ink but further serve to transfer an even film of ink to the plate cylinder for the printing operation.

The assembly of the press contains two sets of corresponding rollers as described. The housing for the rollers is set to provide under a connecting bridge 10 access to the inner sides of each set. This spacing is relatively narrow and it is through this archway that the inking rollers mounted on the inner sides are removed and installed.

Shown by Figs. 4 and 5 the new truck is provided with a frame member 11 formed with an elongated narrow body portion 12 and a flared wider end portion 13. Adjacent the free end or front end of portion 12 the frame is supported by wheels 14 mounted on an axle 15 fixed to the frame. At the opposite or rear end of frame 11 caster wheels 16 are mounted to support the frame at the outside edges of end portion 13.

At each end of the narrow portion 12 brackets 17 (Figs. 1, 2 and 3) are mounted thereon as by bolts or rivets 18. Bracket 17 includes a base member 19 having a socket 20, a post 21 received in socket 20, and a T-shaped roller shaft support 22 mounted on the top of post 21 in the socket 20 of the support.

Support 22 provides a horizontally disposed shelf member with a notch 24 cut centrally of the bracket to receive the shaft of an inking roller as will be described. In a longitudinal channel 25 of the support an extension arm 26 is slidably carried and may be extended beyond either end of the support to overhang either side of the truck. Arm 26 as best shown by Figs. 3 and 6 is preferably provided with a pair of holes 27 for registration with holes 28 in each side of the support 22. A pin 29 is inserted in registered holes 27 and 28 to peg the extension arm 26 in a fixed position when a roller is being removed or installed as will be described.

It will be noted in the drawings that tracks are provided across the plates of the press archway in the form of channel iron guard rails 31. The runways 32 are set for floor level passage of the front wheels 14 directly onto the rails into the archway. The truck is guided into position by the rails 31 which are preferably provided for the full length of the archway as shown by Fig. 4, a—*a* indicating the front and rear boundary lines of the press unit.

In this position within the archway the arms 26 are extended to one side of the truck to under-

lie each end of a roller shaft in the assembly. In the detail view of Fig. 8 the shafts will be noted as carried in a press frame bearing with a removable cap 33. When the cap is removed the shaft is released for passage onto a cradle arm 34 of the socket where it may be manually rolled out of the cradle onto the extension arm 26 and over the slightly inclined top of shelf 22 into notch 24 of the bracket roller support. The arms 26 are then retracted and the roller is wheeled by the truck away from the press and to a cleaning or repair section. A roller is installed in position on the press by reversing these steps described.

It will be noted that during the entire operation of removal from or installation of a roller on a press unit the weight of the roller is entirely supported by the truck unit and is supported at each end of the shaft to prevent damage of any nature to the cylindrical roller surface.

Tilting of the truck is prevented by the guard rails 31 retaining wheels 14 at the front thereof. The rear wheels 16 being set apart at the wide end portion 12 prevent tilting at that end and being of the caster type are used in steering the truck from place to place.

While rails 31 are preferably for the full length of the archway for guiding to roller removing or installing position a short length of channel iron or other means to retain the wheels flat at this location would suffice to prevent tilting.

As described, a post 21 is removable from the bracket assembly of base, post, and roller shaft support and, as will be seen by Fig. 3, a higher post is used for handling the higher rollers 7. A post of an intermediate height may be used for handling of roller 6. Rollers 4 and 7 on the outer sides of the press may be removed by wheeling the truck at either side.

What I claim is:

1. Apparatus to handle inking rollers of an arch type printing press having spaced sets of shaft suspended rollers mounted at each side of said press, said apparatus comprising a truck frame, a narrow elongated portion thereof for passage between said spaced sets of rollers, a bracket at each end of said narrow portion, each of said brackets including a base attached to said frame, a vertical post removably carried thereby, a horizontally disposed holder removably mounted on the post and a sliding arm carried by said holder for lateral extension at each side thereof to receive and support one end of a roller shaft, a pair of wheels on a fixed axis supporting said frame at the front thereof and guide rails of channel iron fixed edgewise between said spaced roller sets to guide and hold said wheels, said frame having a widened end portion and caster wheels mounted at the outer edges of said end portion.

2. Apparatus for the removal and installation of inking rollers of an arch type newspaper printing press having two spaced sets of rollers, said rollers being mounted on shafts at different positions of elevation at each side of the press, said apparatus comprising a truck frame with a narrow elongated portion and a widened rear end portion, a pair of wheels on a fixed axis supporting the outer end of said narrow portion, a pair of caster type wheels supporting the rear end portion at the outer side edges thereof, roller shaft supporting brackets at each end of the

narrow portion comprising a base fixed to the frame and having a vertical post receiving socket therein, a post removably carried in the socket, and a horizontally disposed shaft support having a socket mounting received by said post, said shaft support having a horizontally longitudinal channel therethrough and a slidable extension arm within the channel, said arm and said support being provided with spaced openings in each for registration thereof in extended position of said arm at either side of the support, a holding pin carried by said registered holes, and a notch cut centrally in the support, whereby said arms in extended position are adapted to receive opposite ends of a roller shaft for the supported transfer of a shaft to and from said notch in the support.

3. Apparatus for removing and installing inking rollers of an arch type printing press having spaced sets of rollers supported on shafts and removably held thereby at each side of said press, said apparatus comprising a wheeled frame with an elongated narrow portion for passing between said spaced sets of rollers and having a rear end portion adapted to remain outside said press, spaced roller carrying brackets fixed on the narrow portion adjacent each end thereof to hold the ends of a roller shaft, each bracket having an arm laterally extendable to either side of said frame, a pair of wheels on a fixed axis supporting said frame at the front thereof and guide rails of channel iron fixed edgewise between said spaced roller sets to guide and hold said wheels, said rear end portion of the frame being widened and having caster wheels mounted at the outer edges of said end portion.

4. Apparatus for removing and installing inking rollers of an arch type printing press having spaced sets of rollers supported on shafts and removably mounted thereby at different positions of elevation at each side of said press, said apparatus comprising in combination, a wheeled frame with an elongated narrow portion for passing between said spaced sets of rollers and having a widened rear end portion adapted to remain outside said press, spaced roller carrying brackets fixed on the narrow portion at each end thereof to hold each end of a roller shaft, each bracket having centrally positioned means to cradle said shaft in the transportation of a roller by said apparatus and an arm laterally extendable to either side of said means and narrow frame portion, a removable support carrying each of said cradling means at a predetermined elevation, a pair of wheels supporting the front end of said frame and guide rails fixed between said spaced roller sets with truck holding means to prevent tipping of said truck and caster wheels supporting said widened rear end portion of said frame.
